CARTRIDGE-CHECK FOR MAGAZINE-RIFLES.

1,318,200.

Specification of Letters Patent.

Patented Oct. 7, 1919.

Application filed November 1, 1918. Serial No. 260,737.

To all whom it may concern:

Be it known that I, ABEL FERNANDEZ, a citizen of Mexico, residing at Mexico city, Estados Unidos Mexicanos, have invented 5 certain new and useful Improvements in Cartridge-Checks for Magazine-Rifles, of which the following is a specification.

This invention relates to improvements in magazine rifles and it is the principal object of the invention to provide a novel form 10 of cartridge check adapted for use in connection with magazine rifles whereby the automatic feeding of the cartridges into the breech portion of the rifle for positioning in 15 the firing chamber thereof can be discontinued at will by a user, but which is so arranged and constructed as to permit manual insertion of cartridges into the firing chamber from the breech portion of the 20 rifle, thus accommodating slow firing of the rifle and in consequence, maintaining a reserve supply of cartridges in the magazine instantly available for use as in the event of 25 emergency wherein rapid firing of the rifle is desired.

It is also an object of the invention to provide a check of the character mentioned 30 which will not in any way hinder or interrupt the ordinary usage of the rifle and 35 which can be applied thereto in the form of an attachment with but slight alteration to the rifle.

Another and equally important object of the invention is to provide the rifle with an 35 additional magazine compartment or receptacle allowing the same to accommodate a greater number of cartridges and which can be easily and quickly detached when it is so desired.

40 Other objects will be in part obvious and in part pointed out hereinafter.

The improvements in the details and arrangement of parts will be apparent from an inspection of the accompanying drawings 45 when considered in connection with the specific description hereinafter contained and wherein a preferred embodiment of the invention is shown for the purpose of imparting a full understanding thereof.

50 In the drawings:

Figure 1 is a fragmentary side elevation of the Mauser type of rifle having the improved cartridge check and supplemental magazine applied thereto,

55 Fig. 2 is a top plan view of the same,

Fig. 3 is a detail in perspective of the supplemental or additional magazine receptacle,

Fig. 4 is a vertical fragmentary transverse section through the rifle showing the 60 engagement of the check in the breech portion thereof and the engagement of said check with a cartridge,

Fig. 5 is a fragmentary horizontal section 65 through a portion of the rifle showing the manner of mounting the check on one side thereof and the engagement of the same through the adjacent side of the rifle,

Fig. 6 is a detail in perspective of the improved check,

Fig. 7 is a detail in perspective of the plate to which the same is pivoted,

Fig. 8 is a detail in perspective of the spring pawl employed, and

Fig. 9 is a reduced detail in perspective 75 of the keeper for receiving the projecting tongue carried on one end of the supplemental magazine receptacle.

Having more particular reference to the drawings, in connection with which like reference characters will designate corresponding parts throughout the several views, it is to be noted at this time that I have shown the improved cartridge check applied to a Mauser type of magazine rifle. However, 85 the check can of course be applied to various forms of magazine rifles, such as conditions or preference may dictate. The Mauser rifle is fragmentarily shown and designated in its entirety by the numeral 1, having the 90 ordinary breech portion 2 and a breech block 3 slidable therein, which block is provided with a suitable bolt 4 for an obvious purpose. The magazine chamber is arranged in the side portion of the rifle beneath the 95 breech portion 2 and of course communicates therewith, said chamber comprising a casing or housing 4 into which cartridges are placed for feeding to the breech portion of the rifle. A supplemental or additional 100 magazine receptacle 5 is provided and has its upper end flanged and adapted for engagement with the lower marginal portion of the casing 4; tongues 6 and 7 being formed on and projecting laterally from the opposite ends of the same, one thereof being apertured to permit the engagement of a spring pressed latch pin 8 therein, while the remaining tongue is adapted to be engaged

105 in a keeper 9 secured to an adjacent portion 110

of the rifle stock, thus, permitting the receptacle 5 to be detachably secured in position with respect to the main magazine casing 4. The cartridges are of course fed upwardly 5 into the breech portion of the rifle by means of a spring element 10 arranged in the magazine and having its free end engaged with the ordinary form of follower plate 11, on which the lowermost of the cartridges rest. 10 In this way, the cartridges will of course be fed in sequential order into the breech portion of the rifle for arrangement in the firing chamber thereof.

Pivoted to one side of the rifle adjacent 15 the breech portion 2 thereof is the improved check, comprising an arm 12 having one end thereof reduced and apertured as at 13 and formed with ratchet teeth 14, said reduced portion 13 being pivoted between apertured 20 bearing lugs carried on the slotted plate 15 which is connected to said side of the rifle by screws or similar fastening devices 16. A spring pawl 17 is also secured to one end portion of the plate 15 and has the free end 25 thereof disposed for engagement in the ratchet teeth 14 formed on the reduced apertured portion 13, whereby to releasably secure the arm comprising the check in its operative position with relation to the 30 breech portion of the rifle. A laterally and inwardly extending lip 18 is formed on the outer portion of the arm 12 and is adapted to be passed into the breech portion 2 of the rifle by way of an opening 19 formed in the 35 adjacent portion of the side wall of the rifle, said lip extending into the breech portion 40 said lip extending for a distance sufficient to permit engagement between the same and the uppermost cartridge *c* arranged in the magazine.

Obviously, due to the connection between 45 the lip and the cartridge, upward movement of said cartridge into the breech portion of the rifle for positioning in the firing chamber thereof will be prevented. To facilitate movement of the arm 12 a finger piece 20 may be and preferably is formed or otherwise arranged on the upper side of the outer portion of said arm. It is to be further noted, that outward pivotal movement of 50 the arm 12 with relation to the adjacent side of the rifle will be prevented due to the mode of hinging or pivoting of the same to the bifurcated lugs on the plate 15, said lugs being formed with shoulders as shown in the 55 Figs. 1, 2 and 5. However, pivotal movement of the arm to permit disengagement of the inwardly extending lip 18 from the uppermost cartridge in the magazine is of course allowed.

In using my improved cartridge check, it 60 will be readily understood by persons skilled in the art that I am enabled to maintain a reserve supply of cartridges in the magazine of a rifle provided therewith merely by swinging the arm carrying the inwardly extending lip into its operative position with relation to said rifle, said lip engaging the uppermost cartridge arranged in the magazine and preventing the upward automatic feeding of the same into the breech portion 70 of the rifle. Further, the arrangement of the lip 18 as well as the arm 12 is such as to allow use of the rifle in the ordinary way and in no manner will it detract from the efficiency of the rifle. Cartridges can of 75 course be manually inserted, one at a time, into the breech portion and thence into the firing chamber of a rifle by a user when desiring to fire the rifle slowly. However, should it be desired to discharge the rifle 80 rapidly, then the arm 12 comprising the check is swung outwardly, thus disengaging the lip 18 from the uppermost cartridge and rendering the supply of cartridges in the magazine instantly available for use. Due 85 to the provision of the additional or supplemental magazine receptacle 5, it will of course be appreciated that an extra number of cartridges can be maintained in reserve by a rifle provided with the device. 90

Manifestly, the construction shown is capable of considerable modification and such modification as is within the scope of my claim, I consider within the spirit of my invention.

I claim:

The combination with a magazine rifle having a lateral opening in its breech communicating with the magazine, of a check comprising a slotted base plate fixed exteriorly of the magazine and having bearing lugs, an arm pivoted in the bearing lugs for laterally swinging movement and having a lip at its free end to project into the magazine through the opening in the breech, the 105 pivoted end of the arm being formed with spaced notches, a leaf spring fixed on the base to lie within the slot therein for the fulcrum thereof upon the breech of said rifle to hold the free end of the spring in position 110 for positive engagement in the notches in said pivoted end of the arm, and a nib formed on the arm for permitting manual movement thereof.

In testimony whereof, I affix my signature 115 hereto.

ABEL FERNANDEZ.
